CLAIM

The ornamental design for an electronic camera, as shown and described.

DESCRIPTION

FIG. 1 is a front, side and perspective view of an electronic camera showing my new design;

FIG. 2 is a front elevational view thereof;

FIG. 3 is a top plan view thereof;

FIG. 4 is a bottom plan view thereof; and,

FIG. 5 is a side elevational view thereof from the right of FIG. 2, the side opposite that shown in FIG. 5 being the mirror image thereof.

The material shown in broken line illustrates a possible environment in which the present invention may be found, but forms no part of the claimed design.
